(57) **CLAIM**

The ornamental design for a face mask, as shown and described.

DESCRIPTION

FIG. 1 illustrates a front perspective view of a face mask; FIG. 2 illustrates a back perspective view of the face mask thereof;

FIG. 3 illustrates a front view of the face mask thereof; FIG. 4 illustrates a back view of the face mask thereof; FIG. 5 illustrates a left side view of the face mask thereof; FIG. 6 illustrates a right side view of the face mask thereof; FIG. 7 illustrates a top view of the face mask thereof; FIG. 8 illustrates a bottom view of the face mask thereof; and,

FIG. 9 illustrates an exploded view of the back perspective view of the face mask thereof.

The broken line showing of the face mask is for the purpose of illustrating portions of the article that forms no part of the claimed design.
